Attorney.

UNITED STATES PATENT OFFICE.

CHARLES E. KELSEY, OF ALBUQUERQUE, NEW MEXICO.

SUPPORT FOR CAMERAS.

1,319,397.

Specification of Letters Patent.

Patented Oct. 21, 1919.

Application filed March 20, 1919. Serial No. 283,793.

To all whom it may concern:

Be it known that I, CHARLES E. KELSEY, a citizen of the United States, residing at Albuquerque, in the county of Bernalillo 5 and State of New Mexico, have invented certain new and useful Improvements in Supports for Cameras, of which the following is a specification.

This invention relates to foldable supports, for photographic cameras and other similar articles, which form a tripod when opened and which form a walking-stick or cane when folded; and it consists in the novel construction and combination of the 15 parts hereinafter fully described and claimed.

In the drawings, Figure 1 is a side view of the support when folded. Fig. 2 is a side view of the support when opened. Fig. 20 3 is a detail side view of the pivot joint of one of the legs. Fig. 4 is a front view, and Fig. 5 is a plan view, of the same. Fig. 6 is a side view of the spring catch for securing the handle to the head plate. Fig. 7 25 is a plan view of the same. Fig. 8 is a side view of the catch for connecting the slide stem to the head plate; and Fig. 9 is a plan view of the same.

The support is provided with a circular 30 head plate 2, which has three forked sockets 3 secured to its underside and arranged radially of it. Three legs 4 are provided, and are so shaped that when closed together, as shown in Fig. 1, they form a tapering 35 walking-stick or cane. Blocks 5 are secured between a pair of thin plates 6, and are arranged at the tops of the legs. The plates 6 of each block are secured by rivets in longitudinal slots in the upper end portion 40 of one of the legs, and the block 5 is pivoted in one of the sockets 3 by a pin 9.

When the legs are spread apart, as shown in Fig. 2, they form a tripod. The bottom ends of the legs are preferably provided 45 with spikes 10, and a removable cap 12 of any approved construction is slipped over the spikes and the lower end portions of the legs.

This cap is held in place by any suitable 50 fastening catch or means, and a ring 14 is slid over the cane to prevent the middle parts of the legs from spreading apart.

A central guide tube 15 is secured to the head plate, and projects downwardly between 55 the legs. A central stem 16 is slideable vertically in the guide tube, and is also

revoluble in it. This stem has a collar 17 and a screwthreaded projection 18 at its upper end, for engaging with the camera or other article to be supported, but any other approved means may be used for attaching the article to the upper end of the stem 16. The stem 16 has a longitudinal recess 19 in one side, and 20 is a spring catch secured at one end to the stem by rivets 21, 65 and arranged in the said recess. The catch 20 has an inclined side portion which engages with the central guide tube 15, so that the catch is pressed inwardly and slides through the guide tube when the stem is 70 raised. The catch springs outwardly after passing through the guide tube and its shoulder engages with the head plate 2, so that the stem is held in its raised position until the catch is pressed in by hand. 75

The bottom end of the stem 16 is provided with a screwthreaded projection 24, and 25 is a thumb-nut which is screwed on the said projection. When the stem is raised, as shown in Fig. 8, the nut is screwed against 80 the lower end of the guide tube, so that the shoulder of the catch 20 is moved downwardly and pressed tightly against the head plate. The stem is thereby locked tightly in the guide tube, and is prevented from 85 revolving after the camera has been adjusted.

A handle 26 is provided, and is of any suitable or ornamental shape. A cylindrical 90 socket is secured to the handle, and is slideable over the head plate and the upper end portions of the legs, when the legs are folded together. A spring catch 28 is secured on the outside of the socket 27 by a plate 29 and suitable screws or rivets 30, and the 95 upper end portion of this spring catch projects through a longitudinal slot 31 in the side of the socket and is provided with a laterally projecting detent 32 near its upper end. This detent engages automatically 100 with the head plate when the handle is connected to the cane, as shown in Fig. 1. In order to release the detent a curved lever 34 is pivoted by a pin 35 to a ring 36 which is secured inside the handle. One end 37 of 105 this lever projects laterally through a hole in the handle and forms a push button, and its other end bears against the upper end portion of the spring catch above its detent.

The screw 18 for holding the camera slips 110 inside the ring 36 when the handle is in place, and the ring protects the screw

threads from injury. The legs are suitably grooved on the inside of their upper end portions so that they may fit around the guide tube and slideable stem when folded together. 5 The socket 27 has a slot 38 at its bottom edge which engages with a pin 39 on one leg, so as to prevent the handle from revolving on the legs when secured to the cane. A support constructed in this manner forms 10 a steady base for a camera when set up, and is very convenient to carry.

What I claim is:

1. In a support, a head plate provided on its underside with three forked sockets, 15 three legs adapted to be folded together, each leg being provided with longitudinal slots in its upper end portion, plates secured in the said slots and projecting upwardly therefrom, blocks secured between the projecting 20 portions of the said plates, pins pivoting the said plates and blocks in the said sockets, and means for supporting an article above the said head plate.
2. In a support, a head plate, foldable legs 25 pivotally connected with the said head plate, a guide tube projecting downwardly from the head plate, a stem normally slideable and revoluble in the guide tube, a spring catch

secured to the stem and provided with a shoulder which bears on the upper side of 30 the head plate when the stem is raised, and a thumb-nut screwed on the lower end portion of the stem and adapted to bear against the lower end of the guide tube and clamp 35 the shoulder of the spring catch against the head plate.

3. In a support, a head plate provided with sockets, foldable legs pivotally connected with the said head plate and sockets, a handle provided with a cylindrical socket 40 which is slideable over the head plate and the upper end portions of the legs, said socket having a longitudinal slot, a spring catch having its lower end portion secured to the outside of the socket and projecting 45 through the said slot and provided with a detent for engaging with the head plate, and a curved lever pivoted to the handle with its upper end projecting therefrom and forming a push-button and with its other 50 end bearing against the upper end portion of the spring catch.

In testimony whereof I have affixed my signature.

CHARLES E. KELSEY.
